UNITED STATES PATENT OFFICE.

FRANK L. DYER, OF MONTCLAIR, NEW JERSEY.

INTERNAL-COMBUSTION ENGINE.

No. 1,007,278.

Specification of Letters Patent. Patented Oct. 31, 1911.

Application filed September 20, 1906. Serial No. 335,381.

To all whom it may concern:

Be it known that I, FRANK L. DYER, a citizen of the United States, and a resident of Montclair, in the county of Essex and State of New Jersey, have invented certain new and useful Improvements in Internal-Combustion Engines, of which the following is a description.

My invention relates to internal combustion engines wherein a plurality of cylinders are used, each of which normally operates as a four-cycle internal combustion engine and which are so arranged that the power stroke occurs at a different time in each, so as to provide a practically continuous application of power to the main shaft.

My invention has for its object the provision of means whereby such an engine may be readily started or gotten into operation, which means consist more particularly of devices whereby each cylinder may be converted into a compressed air engine operating to admit air at the beginning of every forward or downward stroke of the piston, allowing the same to expand as the piston advances and then exhausting during the return or upward movement of the piston.

My invention has for its further object the application of such a device to a multiple cylinder engine so that all the cylinders may be thrown into operation together as compressed air engines, and the said cylinders may then be converted one by one into normally operating internal combustion cylinders.

With these ends in view, my invention consists in the features hereinafter described and claimed.

Reference is hereby made to the accompanying drawings in which—

Figure 1 is a plan view of a four-cylinder engine constructed in accordance with my invention; Fig. 2 is a front elevation of the same; Fig. 3 is a section on line 3—3 of Fig. 2; Fig. 4 is a sectional detail view of the valve for admitting explosive mixture to one of the cylinders and represents also the construction of the exhaust valve; Fig. 5 is a similar view of the valve for controlling the admission of compressed air into the cylinder; Fig. 6 is a perspective view showing certain parts of the mechanism for operat-

ing the valves of a single cylinder; Fig. 7 is a diagrammatic view illustrating the relative positions of the four pistons and cranks of the engine; Fig. 8 is a diagrammatic view illustrating the respective shapes and positions of the cams carried by the controller shaft by which my invention is thrown into and out of operation; Figs. 9, 10, 11 and 12 are diagrammatic views, each of which represents the cams which operate the valves of a single cylinder; these figures taken together represent simultaneous positions of all the cams used in operating the valves of the four cylinders.

The engine illustrated comprises four cylinders *a*, *b*, *c* and *d* which are bolted to a crank case *e* in the usual manner and each of which is provided with a piston *f* and connecting rod *g* secured to a crank on the main shaft *h*, the relative arrangements of pistons and cranks being that which is usual in a four cylinder engine of this type, that is, the cranks are placed at intervals of 90 degrees around the crank shaft (see Fig. 7).

Each cylinder is provided with an inlet port *1* closed by a valve *2*. Any form of valve may be used but I prefer the usual form of poppet valve having a stem *3*, as shown in Fig. 4. The inlet pipe *1'* draws its supply of explosive mixture in the usual manner. Each cylinder is provided with an exhaust *4* which is closed by a valve similar to that shown in Fig. 4, and provided with a vertical stem *5*. Each cylinder is also provided with an auxiliary valve *6* which is adapted to admit compressed air to the cylinder from a pipe *7* which is in communication with a compressed air reservoir. The valve *6* may be a balanced valve as illustrated in Fig. 5 wherein a series of ports *8* surround a piston *9* which is provided with longitudinal openings *10* and packing rings *11*. The piston *9* is threaded on a vertical rod *12* which extends upward as shown. Each of the rods *3*, *5* and *12* for operating the valves is surrounded by a coil spring *13* for holding the valve normally in a closed position. The cam shaft *14* is driven from the main shaft *h* at exactly half the speed of the latter in any suitable manner, as by a chain *15* passing over sprockets *16*, and *17*. This shaft carries four cams for each cylin-

der or 16 cams for the four cylinders, namely, cams 1^a, 1^b, 1^c and 1^d for operating the four inlet valves; 2^a, 2^b, 2^c and 2^d for operating the auxiliary compressed air valves; and 3^a, 3^b, 3^c, 3^d and 4^a for operating the exhaust valves. Each of these cams bears against a friction roller 18, carried by a vertical plunger which slides in a bearing frame 20 and is held against rotation by a pin 21 passing through a slot 22 in the plunger. The valve operating mechanism is the same for each cylinder, so it will suffice to describe that shown in detail, in Fig. 6, which is the mechanism of cylinder *d*.

15 The plunger 19^d is operated by the cam 1^d, the plunger 19^a by 2^a, 19^b by 3^b, and 19^c by 4^a. Springs 23 are provided for holding each of the rollers 18 against its respective cam. The valve stems 3, 12 and 5 carry at 20 their upper end plates 24, 25 and 26 respectively. Upon the plate 24 are lugs 27 between which is pivoted a link 28 which extends upward therefrom and is pivoted at 29 to one end of a link 30. The other end 25 of the link 30 is pivoted upon a horizontal pin or shaft 31 which is supported from the frame 20 by means of links 32 depending from brackets or lugs 33 integral with or secured to said frame. The plate 25 is provided with lugs 34 to which is pivoted a link 35. The upper end of the link 35 is pivoted to a link 36 which is pivoted on the pin 31. The plate 26 is provided with a vertical lug 39 whose upper end is immediately below the plunger 19^a. The plate 26 is provided with a lug 40 to which is pivoted a link 41 whose upper end is pivoted to a link 42 which is pivoted on the pin 31. The arm 37 which is integral with one of 40 the arms 32 extends toward the controller shaft 43 and carries a roller 44 for engagement with one of the cams 5^a on said shaft (see Fig. 6), the roller being held against said cam by any suitable means, as a 45 spring 51.

The controller shaft 43 is provided with one cam for each cylinder, namely cams 5^a, 5^b, 5^c and 5^d. The outline of each cam is different, as shown most clearly in Fig. 8, which 50 shows also the respective positions of the different cams. These cams are provided for the purpose of producing certain changes in the operation of the valve mechanism for each cylinder, clearly illustrated in Fig. 6.

55 It will be observed that as the shaft 43 is rotated the cam 5^d acting upon the roller 44 and arm 37 moves the pin 31 in a direction away from the shaft 43, the said arms 32 swinging on their pivots so as to 60 permit such movement, and by reason of this movement the upper end of the link 28 is carried back from under the plunger 19^d so that the valve stem 3 will no longer be operated thereby. At the same time the link 65 35 is carried under the plunger 19^a so that

the valve stem 12 which was formerly will now be operated by the said plunger. Likewise the link 41 will be carried immediately below the plunger 19^a while the a 39 remains in its former position below plunger 19^a so that the valve stem 5 is n operated alternately by plungers. 19^a a 19^d. The upper ends of the links 28, 35 a 41 are beveled as shown in order to cause the link to be pressed downward (as it is turned on its pivot) by whichever plunger is in depressed position at that time. In this n position of parts, therefore, the valve admitting explosive mixture to the cylinder remains permanently closed and each cylinder operates as a single acting compressed air engine admitting compressed air at the beginning of each stroke, cutting the said off after a slight movement of the piston expanding the same and then exhausting during the return of the piston, the exhaust valve being operated alternately by the cam 3^a and 4^a, so as to be opened each time the piston has completed its forward movement. When the parts are in the position shown the plunger 19^d will operate the valve stem 3 through the link 28; the plunger 19^a will move idly since the link 35 is out of its path; the plunger 19^a will operate the valve stem 5 through the arm 39; and the plunger 19^c will operate idly since the link 41 is out of its path. The cylinder will therefore operate as a four-cycle combustion engine.

Since the cams 5^a, 5^b, 5^c and 5^d are of the shapes and relative positions shown in Fig. 8 it is obvious that a movement of the cam in the direction indicated by the arrows will simultaneously convert the cylinders *a*, *b*, and *d* into single acting compressed air engines and since the cranks of the main shaft are set at intervals of 90 degrees one of the pistons will be at or near the beginning of its stroke so that the compressed air entering the cylinder will start the engine, and as the other cylinders successively come into operation the engine will continue to operate and will gain speed very rapidly. As soon as the desired speed has been obtained the movement of the shaft 43 is continued and the cams 5^d, 5^c, 5^b and 5^a thereupon successively restore the valve mechanism of each cylinder to the position of Fig. 6 whereby the cylinder is converted from a compressed air engine to a four-cycle internal combustion engine. The cams are so shaped that the cylinder *d* will first be converted then the cylinder *c*, then the cylinder *b* and then the cylinder *a*. In practice, since the engine will gain speed very rapidly, the operator will give the controller shaft 43 continuous movement and at the end of one complete revolution the engine will be in normal operation as a four-cycle internal combustion engine. The controller shaft 43 also carries a cam 5^x (see Figs. 2 and 8).

which operates a roller 45 and plunger 46 for controlling the compressed air supply of the pipe 7 by means of a suitable valve located at 50 in the said pipe. This valve 5 will be closed when the cam 5* is in the position shown in Fig. 8 which represents the arrangement of parts when the engine is operating as an internal combustion engine. In all other positions of the cam 5* the valve 10 50 will be open for supplying the cylinders with compressed air through the pipe 7.

Having now described my invention, what I claim as new and desire to secure by Letters Patent is as follows:

- 15 1. In an internal combustion engine, the combination with a cylinder, having a piston, and inlet and exhaust valves, and means for operating said exhaust valve at the end of every even numbered forward stroke of 20 the piston, and means for operating said inlet valve, of an auxiliary valve for admitting compressed air to the cylinder at every forward piston stroke, and means for operating the same, and auxiliary means independent of said exhaust valve operating 25 means for operating said exhaust valve at the end of every odd numbered forward piston stroke, and means for simultaneously rendering inoperative the inlet valve operating means, and rendering operative the compressed air valve operating means and auxiliary exhaust valve operating means, while leaving in operation the main exhaust valve operating means, substantially as set forth.
- 30 2. In an internal combustion engine, the combination of a cylinder and piston, an exhaust valve, mechanism for operating said valve at the end of every alternate forward stroke of the piston, a second mechanism for operating said valve and acting alternately with said first mechanism, a member pivoted to said valve, and means for turning said member on its pivot so as to bring it into the path of the second mechanism to thereby 35 operate the valve, substantially as set forth.
- 35 3. In a multiple cylinder internal combustion engine having a plurality of cylinders greater than two, the combination with the cylinders, pistons, inlet and exhaust valves, of 40 mechanisms for operating said exhaust valves at the end of alternate forward piston strokes, auxiliary mechanisms operating alternately with said first mechanisms, movable members, and means for simultaneously moving said movable members into the paths of the auxiliary mechanisms and for successively moving said movable members out of the paths of said auxiliary mechanisms, substantially as set forth.
- 45 4. In a multiple cylinder internal combustion engine, the combination with the cylinders, pistons and exhaust valves, of mechanisms for operating said exhaust valves at the end of alternate forward piston strokes, auxiliary mechanisms operating alternately

with the first named mechanisms, movable members on said valves, and means for simultaneously moving said movable members into the paths of the auxiliary mechanisms and for successively moving said movable members out of the paths of said auxiliary mechanisms, substantially as set forth. 70

5. In an internal combustion engine, the combination of a cylinder, piston, inlet valve, means for operating said valve at every second forward stroke of the piston, an auxiliary valve for admitting compressed air to the cylinder, mechanism for operating said auxiliary valve at every forward piston stroke and a member connected to 75 said auxiliary valve and movable into and out of the path of said mechanism, substantially as set forth.

6. In an internal combustion engine, the combination of a cylinder, piston, inlet valve and means for operating said valve at every second forward stroke of the piston, an auxiliary valve for admitting compressed air to the cylinder, mechanism for operating said auxiliary valve at every forward piston stroke, a member pivoted to the auxiliary valve and means for turning said member on its pivot to bring it into and out of the path of said mechanism, substantially as 80 set forth. 85

7. In a multiple cylinder internal combustion engine having a plurality of cylinders greater than two, the combination with the cylinders, pistons, inlet and exhaust valves, means for normally operating said valves as 90 in a four-cycle engine, an auxiliary valve for each cylinder for admitting compressed air thereto, mechanism for operating said auxiliary valves, members movable into and out of the path of said mechanisms and means 95 so positioned as an actuation to move said members simultaneously into and successively out of the paths of said mechanisms, substantially as set forth. 100

8. In an internal combustion engine, the combination with a cylinder, having a piston and fuel inlet and exhaust valves, of means for normally operating said valves as in a four-cycle engine, an auxiliary valve for admitting compressed air to said cylinder when said valve is operating, a compressed air supply pipe, a valve therein, and means for simultaneously opening said last named valve and so controlling said other valves as to convert the cylinder into a two-cycle compressed air engine, substantially as set forth. 110

9. In a multiple cylinder internal combustion engine, the combination with cylinders having pistons and fuel inlet and exhaust valves, of means for normally operating said valves as in a four-cycle engine, an auxiliary valve for each cylinder for admitting compressed air thereto when said valve is operating, a compressed air supply pipe for sup- 115 120 125 130

- plying compressed air to all said cylinders, a valve therein, and means for simultaneously opening said last named valve and so controlling said other valves as to convert 5 said cylinders into two-cycle compressed air engines, substantially as set forth.
10. In an internal combustion engine, the combination with a cylinder, of valves and valve actuating mechanism therefor de-
10 signed to operate as a four-cycle internal combustion engine, an auxiliary valve for said cylinder, means for actuating said valves, a rock shaft and a revoluble shaft, both axially immovable, and means inter-
15 posable between the said valves and valve actuating means, connected to said rock shaft and controllable from said other shaft for operating said cylinder as a four-cycle internal combustion engine or converting it
20 into a two-cycle fluid pressure engine, substantially as set forth.
11. A plurality of internal combustion motors arranged side by side, a main shaft common to said motors, a shaft parallel to
25 said main shaft, an actuating crank therefor, valves and valve actuating mechanism for the motors designed to operate the same as four cycle internal combustion engines, an auxiliary valve for supplying compressed
30 air, members pivoted to all the valves and movable under the control of the second named shaft, into and out of the paths of said valve actuating means, and operating when moved within the paths thereof to
35 convert the motors into two cycle fluid pressure engines, substantially as set forth.
12. In a multiple cylinder internal combustion engine, the combination with the cylinders, pistons, inlet and exhaust valves,
40 means for normally operating said valves as in a four-cycle engine, an auxiliary valve for each cylinder for admitting compressed air thereto, mechanism for operating said auxiliary valves, members movable into and
45 out of the paths of said mechanisms and of said operating means, connections from said members, and a revoluble member co-acting therewith to so move said members as to convert said cylinders simultaneously
50 into two-cycle compressed air engines and to successively reconver them one at a time into four-cycle engines, substantially as set forth.
13. In a multiple cylinder internal com-
55 bustion engine, the combination with the cylinders, pistons, inlet and exhaust valves, means for normally operating said valves as in a four-cycle engine, an auxiliary valve for each cylinder for admitting compressed
60 air thereto, mechanism for operating said auxiliary valves, members movable into and out of the paths of said mechanisms and of said operating means, connections from said members, and a revoluble member co-acting therewith while being rotated continuously
- for one revolution to so move said members as to convert said cylinders simultaneously into two-cycle compressed air engines and to successively reconver them one at a time into four-cycle engines, substantially as set forth.
14. An engine comprising a plurality of cylinders, each cylinder having valves and actuating mechanism therefor for operating said cylinder as a four cycle internal combustion engine, and also valves and actuating mechanism therefor for operating said cylinder as a compressed air engine, and converting means applied to each cylinder for simultaneously rendering operative one of said actuating mechanisms and rendering inoperative the other of said actuating mechanisms, the converting means for one cylinder being movable independently of the corresponding means for the other cylinder or cylinders, substantially as set forth.
15. An engine comprising a plurality of cylinders, each cylinder having valves and actuating mechanism therefor for operating said cylinder as a four cycle internal combustion engine, and also valves and actuating mechanism therefor for operating said cylinder as a compressed air engine, converting means applied to each cylinder for simultaneously rendering operative one of said actuating mechanisms and rendering inoperative the other of said actuating mechanisms, the converting means for one cylinder being movable independently of the corresponding means for the other cylinder or cylinders, substantially as set forth.
16. An engine comprising a plurality of cylinders, each cylinder having valves and actuating mechanism therefor for operating said cylinder as a four cycle internal combustion engine, and also valves and actuating mechanism therefor for operating said cylinder as a compressed air engine, converting means applied to each cylinder for simultaneously rendering operative one of said actuating mechanisms and rendering inoperative the other of said actuating mechanisms, the converting means for one cylinder being movable independently of the corresponding means for the other cylinder or cylinders, and common means for controlling the movement of each of said converting means, substantially as set forth.
17. In an internal combustion engine, the combination of a cylinder and piston, an exhaust valve, mechanism for operating said valve at the end of every alternate forward stroke of the piston, mechanism operating alternately with and independently of said

first mechanism, and a member movable into a position between said second mechanism and said valve to cause it to operate the said valve, said movement being made without affecting the operative connection of said first mechanism and valve, substantially as set forth.

This specification signed and witnessed this 18 day of September, 1906.
